UNITED STATES PATENT OFFICE.

OTTO BUSCH, OF LIEBERTWOLKWITZ, GERMANY.

DRYING SYSTEM FOR USE WITH ANNULAR KILNS.

Application filed May 14, 1927, Serial No. 191,472, and in Germany September 21, 1926.

This invention relates to a drying system for use with annular kilns in the production of ceramic and similar goods, and the invention consists in the provision of a plurality 5 of parallel drying chambers arranged at opposite sides of the kiln and two series of flues carried across said chambers one above and the other underneath the same, means being provided for supplying combustion 10 gases and hot air from the kiln to said flues for indirect and direct heating of the chambers as well as for returning moist air from the chambers to the flues for admixture with the dry hot air in the latter for a regulation of 15 the temperature.

It should be observed that the employment of flues carried across heating chambers for distributing gases and hot air in the latter is already known.

Fig. 1 of the accompanying drawings represents a horizontal part section of the system taken on the line I—I of Fig. 4,

Fig. 2, another horizontal section on the line II—II of Fig. 3,

Fig. 3, a vertical section on a larger scale taken on the line III—III of Fig. 2,

Fig. 4, a vertical section on the line IV—IV of Fig. 2,

Fig. 5, a vertical section on the line V—V 30 of Fig. 2,

Fig. 6, a vertical section on the line VI—VI of Fig. 2,

Fig. 7, a vertical section taken on the line VII—VII of Fig. 1, and

Fig. 8, a vertical section on the line VIII—VIII of Fig. 1.

Figs. 9 to 12 incl. are diagrammatic illustrations of the circulation of the drying medium.

The drying system comprises two groups of parallel drying chambers 41 arranged at opposite sides of an annular kiln. Carried transversely across these chambers, midway of their length, are two series of flues, one being arranged above and the other below the chambers as shown in Figs. 3 and 4 where the flues in the upper series are designated 21, 22 and 23, and those in the lower series 18, 19 and 20. Each chamber has at the bottom a longitudinal flue 27 (Figs. 5 and 6) which is separated from the chamber by a domed corrugated metal cover 30. The flues 27 communicate through apertures 25 with the flue 19 and through apertures 29 at the ends with flues 31, 32 and 33 (Fig. 2) and through the

latter flues with a chimney. At opposite sides of each flue 27 channels 37 and 38 are arranged which communicate through slits 39 and 40 in the cover plates with the respective chamber and through apertures 24 60 and 26 with the flues 18 and 20 respectively. Above the flue 27 in each chamber there is a gilled pipe 36 through which exhaust steam, if such is available, is led for the heating of the chambers.

At the top of each drying chamber 41 a chamber 43 (Figs. 5 and 6) is provided for the collection of moist air. This collecting chamber is situated between a horizontal partition in which there are apertures 42 and an arched roof in which there are slits 44. The slits 44 open into channels 46 and 48 which communicate through apertures 49 and 51 with the flues 21 and 23 respectively (Fig. 6). Between these channels there is a channel 47 70 which communicates through slits 45 with the chamber 43 and through apertures 50 with the flue 22 (Fig. 5) and through the latter with the discharge flue 33. Along the side walls of the chambers 43 there are gutters 80 43' for the collection and discharge of water of condensation deposited on the walls. The slits 44 and 45 over the chambers 43, and the slits 39 and 40 over the channels 37 and 38 are narrow in the neighbourhood of the transverse distributing flues and widen gradually away from the same, as shown in Figs. 3 and 4, so as to ensure an equal distribution of the air and gases within the drying chambers.

Combustion gases from the kiln are drawn 90 from the flues 4 and 6 by a fan 1 which delivers them through a flue 5 into the flue 19, (Fig. 1). The hot air derived from the kiln by convection and radiation collects in a chamber 16 (Fig. 3) whence it is delivered 95 at the opening of a damper 17 into a pipe 7 which communicates through a pipe 6 with a fan 2 (Fig. 1). The latter feeds the hot air through a flue 8 whence it can be diverted by means of a flap valve 9 (Fig. 8) either into 100 the flue 20 or into the flue 23. The flues 18 and 21 discharge, under regulation by means of a damper 13, into a flue 12 which leads to a fan 3. The latter feeds into a flue 10 which communicates with a chimney 14 but which can also be connected over a damper 11 with the flues 8 and 20.

The intakes and outlets of the different fans are regulated by means of dampers 54. The apertures between the flues and the dry- 110

ing chambers are fitted with regulating dampers. Access to the flues and channels can be had through manholes 52 and 53.

The modus operandi is as follows:

5 After filling the drying chambers with fresh material, a preliminary drying is effected by means of combustion gases which are fed by the fan 1 through the flues 5, 19 and 27. The moist air produced in the chambers 10 is led off to the chimney through the flues 22 and 33, the dampers of the apertures 50 being adjusted according to the available draft. Water of condensation deposited on the walls 15 of the collecting chamber 43, is collected by the gutters 43' and prevented from dripping back into the drying chamber.

When the preliminary drying has proceeded far enough to allow an increase in the temperature, the apertures 24 and 26 are 20 opened. Hot air from the fan 2 will then be supplied to the flue 20, and the moist air will be drawn off by the fan 3 through the flues 18 and 12. The moist air is mainly discharged through the flue 10 and through the 25 chimney 14, but part of the same may be delivered through the flue 23 back into the drying chamber for modifying the temperature, the apertures 51 being opened for this purpose. At a later stage, the apertures 49 are 30 opened so that moist air will be led through the flue 21 to the fan 3. Part of this air is used for mixing with the hot air, as before, the remainder being discharged into the atmosphere. At the end of the drying process 35 the hot flue gases from the kiln may be fed together with the hot air into the drying chambers, the discharge being through the flues 21 and 22. Moreover, exhaust steam, if available, is fed through the pipes 36.

40 By a suitable adjustment of the dampers air mixtures of different kind and temperature may be led in this manner upwards or downwards through the drying chambers to suit the particular goods under treatment, 45 and a very rapid and uniform drying will be

effected while the available heat is utilized to its fullest advantage.

I claim:

1. The combination with an annular kiln of a plurality of parallel drying chambers arranged at opposite sides of the kiln, two series of flues carried transversely across said chambers one above and the other below the same, fans communicating with the different flues, and means for connecting said flues with one another and with the kiln to allow combustion gases and hot air from the kiln to be used for direct and indirect heating of the chambers and allow the moist air from the chambers to be returned to the flues for ad- 60 mixture with the fresh drying air.

2. The structure claimed in claim 1, a chamber arranged between the kiln and one of the fans for collecting the hot air from the kiln, and means for connecting said latter fan 65 with different flues.

3. The structure claimed in claim 1 and a flue carried along the bottom of each drying chamber for indirect heating by means of combustion gases, said latter flue being separated from the respective chamber by means 70 of domed, corrugated metal plate.

4. A drying system according to claim 1 wherein each drying chamber has an arched roof and a perforated partition forming together a chamber for the collection of moist air, and gutters carried along the sides of said chamber for the collection and discharge of water of condensation. 75

5. The structure claimed in claim 1 and 80 longitudinal channels through which the drying chambers communicate with the flues, the communication between said channels and the chambers being effected through apertures the effective area of which is gradually 85 widened in proportion to the distance of the apertures from the flues so as to produce a uniform distribution of the admitted air and gases.

OTTO BUSCH.
